UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed November 20, 1923. Serial No. 675,813.

The invention relates to sound-deadening shoes for typewriting machines. A feature of the invention is the provision of means, or a shaping of the shoe, such that the shoe 5 may be equally applicable to machines of so-called standard construction and machines of special construction, such, for instance, as bookkeeping machines having platens and platen-carriages of greater 10 length, size and weight than the platens and platen-carriages of the standard machines.

A further feature of the invention is the construction of the shoe in two pieces, one 15 to comprise the back and side walls, and the other to be a base-plate; and of means whereby the base-piece may be effectively secured to the other piece to form a strong and rigid unit therewith.

20 A further feature of the invention is a special shaping of the side walls of the shoe to provide clearance for the carriage-runway supports of special machines, and to provide for access to mechanisms, such, for 25 instance, as the ribbon-winding mechanism, so that such mechanisms may be operated without removal of the shoe.

Other features and advantages will hereinafter appear.

20 In the accompanying drawings,

Figure 1 is a view, in side elevation, of the shoe; the same being shown applied to a standard typewriting machine, and one corner thereof being shown as broken away 35 to show the manner in which the parts thereof are assembled.

Figure 2 is a view similar to Figure 1, except that the shoe is shown as applied to a bookkeeping typewriting machine.

40 Figure 3 is a view, in front elevation, of the right-hand end of the shoe and machine.

The shoe comprises a shell, preferably of 45 pressed sheet-metal, and which is in two pieces. One piece, by means of a blanking and forming die, is bent to shape a back wall 10 and two side walls 11. The bends in this piece are so made that, when the shoe is on the machine, the side walls 11 closely 50 embrace the sides of the main frame of the machine below the platen-carriage of the latter. The wall-ports 10 and 11 have embossments 22 and 23, stamped or pressed 55 therein to form ribs to strengthen and add rigidity to the shoe.

The other piece 12 forms the base of the machine. For connecting the base-piece 12 to the first-mentioned piece, the base-piece has a flange 13 turned up from the rear edge thereof, and this flange is secured to the 60 back and side walls of the shoe by spot-welding. The base-piece 12 may also have side flanges similar to the flange 13, whereby it may be welded to the side walls 11; or may have a series of tongues struck up 65 from its edges for welding to the side and back walls.

The back and side walls are lined by a strip or strips 14 of sound-deadening material, such as felt, and the base-piece is lined 70 by a thin sheet 15 of the same or similar sound-deadening material. For retaining the machine against forward displacement in the shoe, there is a flange 16 upturned from the front edge of the base-piece 12; 75 and this flange also preferably has an inner facing 17 of felt or like sound-deadening material. The machine has front feet 18 and rear feet 19 on the bottom of the front and rear corner-posts 20 and 21, on 80 each side of the machine. When the machine is in place in the shoe, the front feet 18 will be set closely to the lining-piece 17 of the flange 16 on the base-plate. As shown in the drawings, the feet 18 and 19 85 rest directly on the top of the base-plate.

Typewriting machines may be of so-called standard construction, that is to say, of construction adapted for ordinary and miscellaneous classes of work, or may be of other 90 than so-called standard construction, as, for instance, such as have carriages of great length for holding large sheets, in the use of the machines for bookkeeping and other purposes. Although, in certain of the features, the machines may differ from one another, yet the base-areas of the main frames of the machines used for these several purposes may be the same; so that the shoe above described may be fitted onto the main 95 frame of any of such machines.

Where, however, as in a bookkeeping machine, the platen and platen-carriage are of great length, and, consequently, have much greater travel than the travel of the platen 105 and carriage of the standard machine, the rails on which the carriages travel on the main frame are of correspondingly great length, and, therefore, are ordinarily supported somewhat differently than the car- 110

riage-runway rails of the standard machine. Furthermore, the supports for the carriage-runways of a bookkeeping machine sustain a weight of carriage which may be much greater than that of the standard machine; and are braced and proportioned accordingly. Commonly, a support for the front carriage-rail in a bookkeeping machine comprises a bracket on each side of the machine, having a rib or ribs curved upward and laterally outward from the front corner-posts of the main frame. These ribs may join such front corner-posts at points which are below the normal and convenient position for the upper edge of the shoe. Such ribs are indicated in the drawings at 24 and 25.

In order that the shoe may be used not only on standard machines, but upon book-keeping or special machines such as described, without interference of the side walls 11 with the bracket-ribs 24 and 25, and in order that the ribs 24 and 25 may clear the upper edges of the side walls 11, whatever the position of the platen-carriage, the upper edges of the side walls are cut down or shaped as at 26. The upper edges of the walls 11 are also recessed at 27 to provide clearance for the support 28 for the rear carriage-rail; and are recessed at 29 to provide clearance for the support for the platen-shift frame.

In order to assure clearance between the side walls 11 and the carriage-supporting ribs or brackets, without too great a cutting of the walls 11 at 26, it may be advisable to interpose heavy washers or blocks 33 between the rubber feet 18 and 19 and lugs 30, to which the feet are secured on the main frame. The feet 18 and 19 are ordinarily secured to the lugs by means of bolts 31, which have heads 32 set into countersinks in the base of the feet, and which extend upward through the feet and thread into the lugs 30. It is only necessary to make these bolts of sufficient length to provide for the interposition of the washers or blocks 33.

For winding or rewinding the ribbon of the typewriting machine, a rotary shaft or spindle is commonly provided. Where a shoe such as described is used, and in order that removal of the shoe may not be required for such winding and rewinding of the ribbon, one of the side walls 11 of the shoe is perforated to permit passage therethrough of a shaft to connect with the shaft or spindle which winds the ribbon. This perforation is shown as a slot 34 in the right-hand wall 11 of the shoe. It is a vertical slot, instead of a mere circular hole, in order to adapt the shoe for use indifferently with a machine such as the standard machine, which sits low in the shoe, and which, consequently, has its ribbon-winding shaft at one position, and a machine which is set higher in the shoe, as by means of the wash-

ers or blocks 33, and which, consequently, has the ribbon-winding shaft at a higher position in the shoe.

Variations may be resorted to within the scope of the invention, and portions of the improvements may be used without others.

Having thus described my invention, I claim:

1. A sound deadening pack or shoe for a typewriting machine, which machine has an upright frame and overhanging front and back part, said shoe comprising a shell in two pieces, one piece being a base plate and the other piece being bent around the edges of the base plate to form a back wall and two side walls of the shoe, the side walls being spaced apart at such distance as closely to embrace the sides of the frame of the machine, the walls of the shoe extending upwardly to approximately the front and back overhanging parts of the machine and the front of the walls of the shoe terminating at the front of the upright frame of the machine, and a sound deadening lining for the shell.

2. A sound deadening shoe for a type-writing machine, which machine has an upright frame and overhanging front and back parts, said shoe comprising a shell in two pieces, one piece being a base plate having a flange or tongue turned up from the edge thereof, the other piece of the shoe being bent around the base plate piece to form a back wall and two side walls, the side walls being spaced apart at such distance as closely to embrace the sides of the frame of the machine, the side walls of the shoe extending upwardly to approximately the front and back overhanging parts of the machine and the front of the side walls terminating at the front of the upright frame of the machine, the side and back wall piece of the shoe being fastened to the flange or tongue of the base plate piece, and a sound deadening lining for the shell.

3. A sound deadening shoe for a type-writing machine of the type that has an upright frame and a front projecting portion, said shoe comprising a shell in two pieces, one piece being a base plate having a flange or rib on the front edge thereof, the other piece of the shoe being bent around the rear and sides of the base piece to form a back wall and two side walls, the side walls being spaced apart at such distance as closely to embrace the sides of the frame of the machine and terminating at the front portion of said frame, the flange or rib of the front edge of the base piece extending in front of the bottom portion of the type-writer frame to retain the machine against forward displacement, and a sound deadening lining for the shell.

4. A sound deadening shoe for a type-writing machine comprising a sheet metal

shell in two pieces, one piece being a base plate and the other piece being bent around the base plate to form a back wall and the two side walls, the side walls being embossed to form strengthening ribs, the base plate piece having a flange or tongue turned up from the edge thereof for attachment to the piece of the shell forming the side walls and back wall of the shoe, and a sound deadening lining for the shell.

5. A sound deadening shoe for a typewriting machine comprising a sheet metal shell in two pieces, one piece being a base plate and the other piece being bent around

10 the base plate to form a back wall and two

side walls, the back wall and two side walls extending upwardly substantially the same distance throughout, the side walls having cutaway portions to accommodate the overhanging parts of the machine and terminating in vertically extending front edges at the front of the typewriting frame, the side and back wall being embossed to form strengthening ribs and the base plate having a flange upturned from the front edge there-

20 of adapted to rest in front of the typewriter feet for retaining the machine against forward displacement, and a sound deadening lining for the shell.

15 ALFRED G. F. KUROWSKI.
